S. D. HENDERSON.

RAILWAY RAIL.

APPLICATION FILED APR. 15, 1919.

1,357,635.

Patented Nov. 2, 1920.

UNITED STATES PATENT OFFICE.

SPARKS D. HENDERSON, OF ST. LOUIS, MISSOURI.

RAILWAY-RAIL.

1,357,635.

Specification of Letters Patent.

Patented Nov. 2, 1920.

Application filed April 15, 1919. Serial No. 290,185.

To all whom it may concern:

Be it known that I, SPARKS D. HENDERSON, a citizen of the United States, residing at the city of St. Louis, State of Missouri, have invented a certain new and useful Improvement in Railway-Rails, of which the following is a specification, reference being had to the accompanying drawing, forming a part thereof.

10 This invention relates generally to railway equipment and, more particularly, to a certain new and useful improvement in railway-rails.

15 The principal objects of my present invention are to provide an efficient rail which may be manufactured and produced with facility and at reduced cost and of which the ball and base are structurally independent, whereby the rail may be conveniently 20 handled and readily installed, the joints of the ball and base units or sections may be staggered or non-coincident and thereby minimize wheel "pounding", and the ball units or sections may be easily removed after 25 installation, for purposes of repair, replacement, and the like, without disturbing or affecting the base units or sections; to provide a rail of the type described in which the ball sections are free to resiliently yield relatively to the fixed base sections under the 30 weight of the cars and form a smooth, cushioned tread or riding surface for the cars; and to improve generally upon rails of the class mentioned.

35 With the above and other objects in view, my present invention resides in the novel features of form, construction, arrangement, and combination of parts hereinafter described and afterward pointed out in the 40 claim.

In the accompanying drawing,

Figure 1 is a plan view of a railway rail embodying my invention;

Fig. 2 is a side elevational view of the 45 rail;

Fig. 3 is an enlarged transverse sectional view of the rail on approximately the line 3—3, Fig. 1;

Fig. 4 is an elevational view showing fragments of two contiguous ball-sections and means for holding the same in a common plane;

Fig. 5 is an enlarged transverse sectional view of the rail on approximately the line 55 5—5, Fig. 1; and

Fig. 6 is an enlarged fragmental longitudi-

dinal sectional view on approximately the line 6—6, Fig. 1.

Referring to the said drawing, in which like reference characters refer to like parts throughout the several views, A—A designate the base sections, which are preferably formed as integral units and of lengths and weights, or sectional dimensions, as desired; and B—B designate the ball or tread sections, which are also preferably constructed as integral units and of lengths and weights or sectional dimensions proportionate with the base units or sections A.

As shown, each base unit A comprises the base flanges 1 and 2, whose bottom faces provide a continuous, both transversely and longitudinally, plane or flat surface arranged for placement on ties or sleepers (not shown), the flanges 1 and 2 being formed or provided with suitable spike-openings or recesses 3 to accommodate suitable spikes for rigidly securing the unit to such ties or sleepers. By preference, flange 1, being the outside flange, has greater width than the inside flange 2, whereby the tendency to rail canting by lateral stresses of rolling-stock is materially lessened and spike-pulling thereby largely prevented, the danger of accidents incident to or resulting from loose rails being correspondingly minimized. Arising from the base flanges 1 and 2 and at a right angle thereto, is a pair of spaced webs 4 and 5, which form an open-top channel 6, and intersecting the channel 6 at intervals longitudinally of the rail-unit, are bolt-holes 7, which preferably are surrounded by outstanding bosses 8. At regular intervals longitudinally of the unit, I provide the unit with strengthening struts or braces 9 between the flanges 1 and 2 and the channel-forming webs 4 and 5, whereby the unit as a whole will be rigid and yet the sectional dimensions be relatively small, the several units or sections A being arranged end to end when installed upon the ties to form the track-way.

Each ball or tread unit B is substantially a T-shape section made up of a ball 10 and a web 11. The webs 11 of the ball units B are adapted to fit in and occupy the channel 6 of the base units A and are provided therethrough with bolt-holes 12 arranged for registration with the bolt-holes 7 of the supporting base-units, whereby the units may be relatively secured by bolts 13 extended through the webs 4, 5, and 11. As seen espe-

cially in Fig. 3, the bolt-holes 7 and 12 are of greater diametrical dimensions than the securing-bolts 13 extended therethrough, whereby expansion and contraction of the units are provided for, and whereby also there may when installed be a vertical movement of the ball-units B relatively to the base-units A.

In forming the track-way, the ball-units B are disposed also end to end with their webs 11 occupying the channel 6 provided by the base-units A, the joints between the ball sections being preferably staggered relatively to the joints between the base-units, as seen in Figs. 1 and 2, and as shown in Fig. 4, the webs 11 of the ball-sections B are preferably provided at their ends with interlocking tongues and recesses 14—15, whereby adjacent or contiguous ball-units are held at their joints to the same plane and pounding of the rolling-stock at the rail-joints obviated or minimized.

To relieve the base-units from shocks tending to disturb their installed position, and also to lessen the vibrations of the rolling-stock, I interpose a cushion 16 preferably in the form of a strip of resilient material or the like, in the channel 6 between the base-units A and the lower edges of the webs 11 of the ball-units B; and to protect the cushion at the joints of the base-units, I provide retainers in the form preferably of channeled or substantially U-shaped sheet-metal bridges 17, which span such joints, as seen in Fig. 6.

I prefer to equip the rail with a cushion such as mentioned, but such cushion may be omitted and the rail be fully operative, and for such purpose the webs 4 and 5 and 11 of the rail-sections are relatively of such height that, with the cushion omitted, the ball-units B will fit the base-units A with their webs 11 supported at their lower edges upon the base of the channel 6 and their ball 10 supported at its under faces 18 upon the upper faces 19 of the webs 4 and 5; and to minimize distortion by hammering or otherwise of the upper edges of the base-webs 4 and 5 when so carrying the load, I provide the base-units with so-called outwardly presented flanges 20 which lengthen the faces 19 of the upper ends of the webs; and preferably the lengthened faces of the webs 4 and 5 so provided are inclined downwardly relatively to the horizontal to fit

and coöperate with the similarly inclined under faces 18 of the ball and thereby provide or form a water-shed for the channel 6 of the base units, the channel 6 being additionally provided with drain-openings or the like 21 for water or other foreign matter which may find entrance into the channel.

The sections of my new rail are of a form and shape, as will be observed, that they may be conveniently and readily installed, and the ball-sections easily replaced when worn or broken or when otherwise required; and the rail as a whole provides a smooth, even tread or riding surface upon which the rolling-stock may travel with reduced vibrations and with little or no wheel pounding.

I am aware that changes in the form, construction, arrangement, and combination of the several parts of my new rail may be made and substituted for those herein shown and described without departing from the nature and principle of my invention.

Having thus described my invention, what I claim and desire to secure by Letters Patent is:

A railway rail including, in combination, a base section integrally consisting of oppositely disposed flanges, one of which is wider than the other, spaced webs rising from the flanges and providing an open-end channel, and web-strengthening-struts disposed between the flanges and webs, the webs being flanged outwardly and thereby widened at their upper edges, a ball-section of substantially T-shape integrally consisting of a ball and a web, the web of the ball-section being adapted to fit and occupy the channel of the base-section and the widened edges of the webs of the base-section being adapted to receive the under faces of and provide a broad-supporting-seat for the ball of the ball-section, the webs of the base-section at their said widened edges and the under faces of the ball of the ball-section inclining correspondingly downwardly relatively to the horizontal, and fastening-members adapted for projection transversely through the webs of the base and ball-sections for securing the sections together.

In testimony whereof, I have signed my name to this specification.

SPARKS D. HENDERSON.
